(57) **CLAIM**

The ornamental design for a hunter's bird release cage, as shown and described.

DESCRIPTION

FIG. 1 is a front perspective view of a hunter's bird release cage, showing my new design;

FIG. 2 is a rear perspective view of the hunter's bird release cage shown in FIG. 1;

FIG. 3 is a front view of the hunter's bird release cage shown in FIG. 1;

FIG. 4 is a rear view of the hunter's bird release cage shown in FIG. 1;

FIG. 5 is a left-sided view of the hunter's bird release cage shown in FIG. 1;

FIG. 6 is a right-sided view of the hunter's bird release cage shown in FIG. 1;

FIG. 7 is a top view of the hunter's bird release cage shown in FIG. 1;

FIG. 8 is a bottom view of the hunter's bird release cage shown in FIG. 1; and,

FIG. 9 is another front perspective view of the hunter's bird release cage shown in FIG. 1, shown with the release mechanism activated so that the cage is in an open position (i.e., bird release).

The dashed broken lines shown in the drawings illustrate portions of the hunter's bird release cage that forms no part of the claimed design.
